United States Patent Office

Des. 217,446
Patented May 5, 1970

217,446

ALL TERRAIN MOTOR VEHICLE

Allen E. Mitchell, 710B West Arrow Hwy., and James L.
Britain, 245 W. 7th St., both of Upland, Calif. 91786

Filed Mar. 21, 1969, Ser. No. 16,370

Term of patent 14 years

Int. Cl. D12—13

U.S. Cl. D14—3

Fig. 1

Fig. 2

Fig. 3

Fig. 4

Fig. 5

FIG. 1 is a top perspective view of an all terrain motor vehicle of our design.

FIG. 2 is a side elevational view thereof.

FIG. 3 is a top plan view.

FIG. 4 is a front elevational view, and

FIG. 5 is a rear elevational view.

The side opposite that shown in FIGS. 1 and 2 is a mirror image thereof.

We claim:

The ornamental design for an all terrain motor vehicle, substantially as shown and described.
